(57) **CLAIM**

The ornamental design for a power and audio adapter box, as shown and described.

DESCRIPTION

FIG. 1 is an isometric, upper front view of the power and audio adapter box according to the present design; FIG. 2 is an isometric, lower front view thereof; FIG. 3 is a front view thereof; FIG. 4 is a rear view thereof; FIG. 5 is a top view thereof; FIG. 6 is a bottom view thereof; FIG. 7 is a left side view thereof; FIG. 8 is a right side view thereof; FIG. 9 is an isometric, upper front view thereof, showing locations of connector sockets to be attached to openings in the front surface of the box; and, FIG. 10 is a front view thereof, showing the box according to the present design installed on a musical amplifier. Broken lines in FIGS. 1-10 showing elements of the power and audio adapter box indicate the bounds of the claimed design and unclaimed subject matter. Additional broken lines in FIG. 10 showing the musical amplifier illustrate the environment in which the article embodying the claimed design is used. Elements shown in broken lines form no part of the claimed design.
